CLAIM

The ornamental design for a straw, as shown and described.

DESCRIPTION

FIG. 1 is an environmental perspective view of a straw in an in-use configuration showing our new design;

FIG. 2 is another perspective view of the straw shown in FIG. 1.

FIG. 3 is a rear, elevation view of the straw shown in FIGS. 1 and 2.

FIG. 4 is a front, elevation view of the straw shown in FIGS. 1 and 2.

FIG. 5 is a left, elevation view of the straw shown in FIGS. 1 and 2.

FIG. 6 is a right, elevation view of the straw shown in FIGS. 1 and 2.

FIG. 7 is a top, plan view of the straw shown in FIGS. 1 and 2.

FIG. 8 is a bottom, plan view of the straw shown in FIGS. 1 and 2.

The broken line in the drawings depict the portions of the straw and the environmental structure and form no part of the claimed design.
